[57] CLAIM

The ornamental design for a combined smoke detector and remote alarm, as shown and described.

DESCRIPTION

FIG. 1 is a perspective view of a combined smoke detector and remote alarm showing our new design, with the wire broken away to indicate indeterminate length;

FIG. 2 is a top plan view of the smoke detector portion thereof, with the remote alarm portion omitted for clarity of illustration only;

FIG. 3 is a bottom view thereof;

FIG. 4 is a front view thereof; and the rear view is a mirror image thereof;

FIG. 5 is a right view thereof;

FIG. 6 is a left view thereof;

FIG. 7 is a top plan view of the remote alarm portion, with the smoke detector portion omitted for clarity of illustration only;

FIG. 8 is a bottom view thereof;

FIG. 9 is a rear view thereof; and the front view is a mirror image thereof;

FIG. 10 is a left view thereof; and,

FIG. 11 is a right view thereof.
